UNITED STATES PATENT OFFICE.

LEVI DA ROZIR, OF CAMBRIDGE, MASSACHUSETTS, ASSIGNOR OF FIVE-EIGHTHS TO FRANK A. TEELE AND LOUIS P. COTÉ, OF SOMERVILLE, MASSACHUSETTS.

AUTOMATIC SHUT-OFF MECHANISM FOR STEAM-ENGINES.

SPECIFICATION forming part of Letters Patent No. 629,778, dated August 1, 1899.

Application filed October 19, 1898. Serial No. 694,021. (No model.)

To all whom it may concern:

Be it known that I, LEVI DA ROZIR, of Cambridge, in the county of Middlesex, State of Massachusetts, have made certain new and useful Improvements in Automatic Shut-Off Mechanisms for Steam-Engines, of which the following is a description sufficiently full, clear, and exact to enable any person skilled in the art or science to which said invention appertains to make and use the same, reference being had to the accompanying drawings, forming part of this specification, in which—

Figure 1 is a side elevation showing the ordinary shut-off valve in the steam-supply pipe of a stationary steam-engine provided with my improved automatic shut-off mechanism; Fig. 2, a top plan view of the same; Fig. 3, a vertical section taken on line 3 3 in Fig. 1; and Fig. 4, a cross-section, enlarged, on line 20 4 4 in Fig. 2.

Like letters of reference indicate corresponding parts in the different figures of the drawings.

My invention relates especially to a safety appliance attachable to a stationary steam-engine, whereby steam may be instantly shut off and the engine stopped from any room of the building in which it is located in the event of accident. Heretofore great difficulty has been experienced in communicating with the engineer in order to stop the engine in time to save the life of persons who might be caught by the shafting in remote portions of the building. Other reasons also frequently arise where it is desirable to immediately stop the engine. My invention is designed to obviate these objections, and in carrying it out I make use of means that will be understood by those conversant with such matters from the following explanation.

In the drawings, A represents the throttle-valve of a steam-engine of ordinary and well-known construction, B the steam-inlet pipe from the boiler, and C the outlet from the valve to the engine, these parts being all of the ordinary form and construction. The stem *f* of the valve is provided with the usual hand-wheel *g*, and on said stem in my improvement is mounted a steam-tight box *D*. The

inlet-pipe *C*, leading to the engine, I tap by 50 a branch *d*, in which a valve *h* is incorporated. This branch *d* leads tangentially into the box *D* at *i*. (See Fig. 3.) From the under side of said box an exhaust *j* leads. On the stem *k* of the valve *h* there is a weighted 55 arm *m*, which normally operates to hold said valve closed and exclude steam from the box *D*. This arm *m* is connected by a wire *p*, leading to various parts of the building in which the engine is located. Fast on the 60 stem *f* of the main valve *A*, within the box *D*, there is a fan-wheel *H*, provided with tangential blades of different lengths *q r* (see Fig. 3) in such position that a jet of steam from the branch *d* will engage and impinge 65 against said blades and rotate said wheel, carrying the stem *f* and closing the main valve *A*.

In use the hand-wheel *g* may be operated to open and close the main valve in the usual manner. When it is desired to stop the engine from any cause without going to the engine-room, by pulling the cord *p* from any portion of the building the arm *m* may be elevated, opening the valve *h*. Steam is thus admitted to branch *d* from inlet *C* and at once 70 expands into box *D* in a jet, which, striking the blade *r* *q*, rotates the wheel *H*. This operates the valve-stem *f*, to which it is fast, and, closing the main valve, shuts off the steam from the boiler in a manner which will be understood by those conversant with such matters without a more explicit description. 75

It will be seen that by the use of the device described the ordinary manipulation of the throttle-valve wheel is in no manner interfered with, as would be the case were an outside mechanism belted thereto. I am aware that such mechanism has been used wherein steam is taken from another source; but in such devices not only is the ordinary use of 80 the throttle greatly hindered, but, steam being applied to an engine incorporated in a separate steam-supply, the full pressure of such steam is maintained after the valve is shut or closed. In my device these objections 85 are obviated. The fan-wheel being mounted directly on the throttle-stem offers no resistance to the ordinary use of said stem, and by 90 95

- taking steam from the engine side of said throttle or direct from the engine-supply I obtain its full force to at once impart sufficient impetus to the fan-wheel to close the throttle. 5 Such steam is, moreover, immediately exhausted from casing D as soon as its work is done, and as the throttle is thus instantly closed by the action of steam direct from the inlet of the engine and said steam is instantly 10 shut off from the fan-wheel as the throttle closes there is no unnecessary escape of steam nor any "bleeding" of the casing D essential before starting up again or operating the throttle by hand to reopen it. 15 Having thus explained my invention, what I claim is—
1. In a steam-engine the throttle-valve provided with a fan-wheel on its stem in combination with a casing inclosing said wheel; an 20 exhaust for said casing; a pipe tapping the steam-supply pipe of said engine, and open-
- ing into said casing; a valve in said first pipe and devices for operating said valve whereby steam-pressure from the engine-supply may be delivered direct to said wheel and said 25 pressure shut off by the consequent closing of said throttle.
2. The throttle-valve and its stem in combination with the valve-inlet, B, and valve-outlet, C; the fan-wheel, H, fast on said stem; 30 the steam-box, D, inclosing said wheel and stem; the branch pipe, d, connecting said outlet, C, between the engine and throttle with said box; the valve in said branch; devices for operating said valve; and an exhaust in 35 said box, all being arranged to operate substantially as specified.

LEVI DA ROZIR.
